UNITED STATES PATENT OFFICE.

EDMOND BUCKLEY, OF SWAN, IOWA.

CAR-COUPING.

SPECIFICATION forming part of Letters Patent No. 394,954, dated December 25, 1888.

Application filed April 7, 1888. Serial No. 269,931. (No model.)

To all whom it may concern:

Be it known that I, EDMOND BUCKLEY, a citizen of the United States, residing at Swan, in the county of Marion and State of Iowa, 5 have invented certain new and useful Improvements in Car-Couplings; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

10 This invention relates to car-couplings, and has for its object the provision of simple, compact, and efficient means for coupling the cars automatically without the necessity of a person going between the cars for coupling or uncoupling them.

15 The improvement consists in providing a draw-bar of novel construction which will admit of the use of the usual coupling link and pin, and which will be provided with an automatic coupling device on each side of the middle draw-bar. One of the said side coupling devices consists of a link and pin, the link being permanently connected with the draw-bar and having its inner end weighted 20 to support the outer end thereof and hold it in a horizontal position, or nearly so. The other side coupling device consists of a gravity-latch of peculiar construction and an extension projecting upward from the bottom 25 of the draw-bar. The draw-head is triple and one side is open to permit of the link being turned out of the way when it is desired that it should not be used in coupling.

30 The improvement further consists of the novel features, which hereinafter will be more fully described and claimed, and shown in the annexed drawings, in which—

Figure 1 is a perspective view of one end of a car provided with my improved coupler; 35 Fig. 2, a side view, parts being broken away, of the coupler; Fig. 3, a front view of the coupler; Fig. 4, a side view of the coupler, looking at the side opposite to that seen in Fig. 2; and Fig. 5, a detail view showing the 40 operation of the gravity-latch.

The draw-bar A has a yielding connection

with the car, and is provided with a triple head formed by the lateral extensions or lugs a and a', there being two of each kind, one above the other, the extensions a' being connected at their outer ends by the vertical bar a². The upper side of the lower of the two extensions a is curved upward near its outer end to hold the link B parallel with the line of draft or in the direction of the length of 55 the car. The two extensions a have vertical openings through which the coupling-pin C passes and holds the link B in place. This pin is held in place by any suitable means, as the plate c, secured to the top lug, a, and fitting in a groove or contracted portion of the said pin. The pin is enlarged at c' just above the link, and this enlargement rests upon the rear end of the link and assists in holding it upon the bottom lug. The pin has a limited 60 vertical movement to permit the link B to move vertically when the cars are coupled.

The link B has one end slotted and the other end solid, and provided with an opening for the pin C. The solid end rests on the bottom 65 lug, a, and possesses sufficient weight to hold the link in a horizontal position, being additionally weighted down by the coupling-pin.

The draw-bar is provided at the middle of its head with the throat D for the reception 70 of the ordinary link-and-pin coupling, (not shown,) and with the upwardly-inclined extensions d, which are closed at their rear edges. The top lug, a', is notched in its rear edge, and is provided with the rear extension, 75 e, and the bottom lug is provided with the stop E, that is inclined on its front and rear edges, and which acts in connection with the gravity-latch F to hold the link of the adjacent car.

80 The gravity-latch is provided with the ears f, which embrace the top lug, a', and with the rear extensions, f' f². The lower end of the latch inclines upwardly from a middle point in an opposite direction to the inclined edges 85 of the stop E. The latch is held to the top lug by the pin G, that extends through the oblong slot f³ in the top ear, f. The rear side of the top lug, a', is vertical, and the front edge of the gravity-latch is also vertical and 90 bears against the rear side of the said lug a'. The link on entering between the lugs a'

rides over the stop E and pushes the gravity-latch backward and upward until it enters sufficiently far, when the latch gravitates and holds the link between it and the stop. The 5 rock-shaft II, having its ends *h* bent at right angles and provided with the arm I and the lifting-hook *i*, that extends beneath the rear extension, *f'*, is adapted to uncouple the cars by effecting an elevation of the rear end of 10 the coupling-latch, when the link is free to ride over the stop. The ends *h* are flexible and embrace the sides of the car with a certain degree of tension. The strip J, secured to one side of the car and having a notch, *j*, 15 holds the latch elevated when the rock-shaft II is turned, so that the arm *h* will spring into the said notch *j*. This strip is beveled, so that when the latch is down the arms *h* will not exert any binding action and impede the free 20 movements of the said latch.

It will be understood that each end of the car will be provided with my improvement, and that the couplers will be so disposed that the draw-heads on the opposing ends of two 25 cars will have the link of one coupler opposite the gravity-latch of the other coupler. Now, when the cars are run together a double link-connection is had between them. At any rate the chances for coupling are two to 30 one over the general run of couplers. The link can be turned at right angles to the draw-bar when it is desired to have it out of the way, as when coupling the car by the ordinary link and pin. This arrangement permits the coupler to be used on a wide range 35 of cars and with the ordinary coupler.

Having thus described my invention, what I claim, and desire to secure by Letters Patent, is—

40 1. The herein-described coupler, composed of a draw-bar having top and bottom lugs to form a triple draw-head, two of the lugs be-

ing united by a vertical bar and the bottom lug of the two having a stop on its upper side, the bottom lug of the other two lugs 45 being upwardly curved at its outer end, the link weighted at its inner end and held on said curved lug and free to be turned to one side, the gravity-latch having ears that embrace the top lug of the said two united lugs, 50 and having its lower end inclined upwardly in each direction from a middle point, and having a rear extension and means for engaging with the said gravity-latch for moving it, substantially as and for the purpose de- 55 scribed.

2. The combination, with the draw-bar and the link having its inner end weighted, of the pin having an enlargement which rests on the link, and having a groove or contracted 60 portion, and the plate fitted in the said groove and secured to the draw-bar to limit the vertical movement of the pin, substantially as described.

3. The combination, with the draw-bar having the double-inclined stop E at its lower side, and having its upper portion, *a'*, notched on its rear side, of the gravity-latch F, having the lugs *f* at its front edge, which embrace the top and bottom sides of the said portion *a'*, 70 and having the rear extensions, *f'* and *f''*, and having its lower end adapted to rest on the stop E and sloping in each direction, the pin G, passing through a slot, *f³*, in the upper lug, *f*, and the operating-lever connected with the upper rear extension, *f'*, substantially as specified.

In testimony whereof I affix my signature in presence of two witnesses.

EDMOND BUCKLEY.
